FUR STRETCHING AND FASTENER APPLY-
ING IMPLEMENT

Joseph Steiner, deceased, late of Toronto, Ontario, Canada, by Florence G. Steiner, administratrix, Toronto, Ontario, Canada

Application December 6, 1948; Serial No. 63,784

4 Claims. (Cl. 1—45.6)

1

In the preparation of furs and skins for manufacture into garments, it is usual to treat the skins by stretching them and tacking them on a board or block while in said stretched condition until such time as they have lost their tendency to contract when freed.

It is a rather difficult operation to first stretch the skin and hold it in stretched condition while the tacking is taking place, and the object of the present invention is to devise apparatus which will grip the skin to enable it to be stretched, and which, without losing the grip on the skin, will automatically drive staples or tacks to hold the skin to the board in said stretched condition.

This object is attained by means of the constructions hereinafter described and illustrated in the accompanying drawings in which

Fig. 1 is a perspective view of the apparatus ready for gripping a skin to stretch it;

Fig. 2 a similar view showing the parts gripping a fur and ready to effect the driving of a staple;

Fig. 3 a plan view of the apparatus; and

Fig. 4 a vertical longitudinal section through the staple carrier.

In the drawings like numerals of reference indicate corresponding parts in the different figures.

The apparatus includes a pair of pliers comprising a pair of members 1 and 2 pivoted together at 3 to rock on a horizontal axis. The member 1 comprises the lower jaw 4 and operating handle 5, while the member 2 comprises the upper jaw 6 and operating handle 7. A spring 8 is provided between the handles 5 and 7 tending to hold the latter apart and thus force the jaws 4 and 6 together. The adjacent faces of the jaws will be suitably serrated or roughened to more firmly grip the skin 9, which is indicated in dotted lines.

Extending transversely of the upper jaw 6 is the staple magazine 10, in which the staples are mounted on a guide 11 along which they are moved to the driving position by a sliding member 12 operated by a spring 13.

Extending upwardly from the end of the magazine is a guide 14 in which is vertically slidable the hammer 15, which is provided with a head 16 by means of which it may be manually operated when desired.

It is preferred, however, that the control of the hammer be automatic, and to effect the driving of the hammer a leaf spring 17 is provided having one end secured to the upper side of the staple magazine and its free end projecting into a notch 18 in the hammer. This leaf spring nor-

2

mally tends to move the hammer downwardly to drive the staple.

Extending upwardly from the upper jaw 6 slightly in advance of the pivot 3 are posts 19 in which is journaled a shaft 20 from which extends a post 21 on which is horizontally swingable a bent lever 22. One end of this lever 22 is provided with spaced pins 23 which extend one above and one below the handle 5, so as to cause said lever to swing on the shaft 20 with said handle 5. The other end of this lever is adapted to engage under a shoulder 24 on the side of the hammer 15. A spring 25, having one end connected with the lever and its other end connected with an arm 26 extending from one of the posts 19, tends to hold the lever engaging under the shoulder 24 in hammer-lifting position.

The operation of the device is as follows. The jaws 4 and 6 are forced together to grip the skin between them and by pulling on the device the skin is stretched to the desired extent. In forcing the jaws 4 and 6 together, the handle 5 rocks the lever 22 in the vertical plane to lift the hammer 15 and the hammer is thus held raised while the skin is being stretched. When the skin is sufficiently stretched, the lever 22 is rocked sidewise on the pivot 21 (see Fig. 3) to disengage the end of the lever from the shoulder 24, to allow the spring 17 to force the hammer downwardly heavily against the staple below to drive the latter. When the staple is driven, the handles 5 and 7 are allowed to separate and a new grip is taken at another position of the skin to stretch it. Upon separation of the handles 5 and 7, jaws 4 and 6 also separate and since lever 22 is carried by handle 7 at its jaw end 6, outward movement of handle 5 resting between pins 23—23 of lever 22 rocks the opposite end of the lever 22 to place its end in line with the notch 18 on the hammer, where the end is then moved below the shoulder 24 in the hammer.

It will be seen that the work of stretching the skin and driving the staples may be done by one person, whether the hammer is manually or automatically operated. In the case of the automatic operation of the hammer, the stretching of the skin and driving of the staples may be done with one hand.

It will be understood that various alterations may be made in the shape and arrangement of the various parts without departing from the spirit of the invention.

What is claimed is:

1. In a fur blocker and fastener, the combina-

tion with a pair of lever members pivotally connected intermediate their ends to form opposed gripping jaws at one side of the pivot and opposed handles at the other side of the pivot, of a fastener magazine mounted on one of the jaws and having a fastener outlet beyond the gripping surface of the jaw; a hammer movable to and from the outlet; spring means normally tending to move the hammer towards the outlet; means operable by a handle for engagement with the hammer to move the hammer away from the outlet against the action of the spring; and means for disengaging said engageable means to permit the spring to move the hammer towards the outlet.

2. In a fur blocker and fastener, the combination with a pair of lever members pivotally connected intermediate their ends to form opposed gripping jaws at one side of the pivot and opposed handles at the other side of the pivot, of a fastener magazine mounted on one of the jaws and having a fastener outlet beyond the gripping surface of the jaw; a hammer movable to and from the outlet; spring means normally tending to move the hammer towards the outlet; a hammer-controlling lever pivotally supported intermediate its ends on said magazine-carrying jaw; means at one end of said hammer-controlling lever engageable by the handle of the opposing jaw, the other end of said hammer-controlling lever being adapted to engage with the hammer to move the hammer away from the fastener outlet; and means to release the hammer to permit the spring to move the hammer towards the fastener outlet.

3. In a fur blocker and fastener, the combination with a pair of lever members pivotally connected intermediate their ends to form opposed gripping jaws at one side of the pivot and opposed handles at the other side of the pivot, of a fastener magazine mounted on one of the jaws and having a fastener outlet beyond the gripping surface of the jaw; a hammer movable to and from the outlet; spring means normally tending to move the hammer towards the outlet; a

hammer-controlling lever pivotally supported intermediate its ends on said magazine-carrying jaw, means to swing said hammer-controlling lever in the same plane as the lever members and also in a plane transversely thereof; means at one end of said hammer-controlling lever engageable by the handle of the opposing jaw, the other end of said hammer-controlling lever being adapted to engage with the hammer to move the hammer away from the fastener outlet; and means to release the hammer to permit the spring to move the fastener outlet to drive a fastener.

4. In a fur blocker and fastener, the combination with a pair of lever members pivotally connected intermediate their ends to form opposed gripping jaws at one side of the pivot and opposed handles at the other side of the pivot, of fastener feeding and driving means mounted on a gripping jaw and having a fastener outlet beyond the gripping surface of the jaw, said fastener feeding and driving means including resilient means tending to move the driving portion of said means towards the fastener outlet; and means adapted to engage with the driving portion to move said driving portion away from the fastener outlet; and means to release the driving portion to allow the resilient means to move the driving portion towards the fastener outlet.

FLORENCE G. STEINER,
Administratrix of the Estate of Joseph Steiner,
Deceased.
